UNITED STATES PATENT OFFICE.

WALTER S. ALLYN, OF LOGAN, ILLINOIS, ASSIGNOR OF ONE-HALF TO EARL V. AKIN,
OF BENTON, ILLINOIS.

CAR-STOPPING ATTACHMENT FOR ELEVATORS.

1,398,619.

Specification of Letters Patent.

Patented Nov. 29, 1921.

Application filed November 22, 1920. Serial No. 425,717.

To all whom it may concern:

Be it known that I, WALTER S. ALLYN, a citizen of the United States of America, a resident of Logan, in the county of Franklin, State of Illinois, have invented certain new and useful Improvements in Car-Stopping Attachments for Elevators, of which the following is a full, clear, and exact description, reference being had to the accompanying drawings, forming a part of this specification.

This invention relates to improvements in car stopping attachments for elevators, one of the objects being to produce a car stop adapted to be automatically released when the elevator reaches a predetermined position, and thereafter positively restored before the car passes from the elevator.

A device of this kind is especially adapted for use in mines, where one car is pushed from an elevator while another car is passing onto the elevator, it being customary to use a loaded car moving onto the elevator as a means for pushing an empty car from the elevator. Following the ordinary practice, this operation is carried out very rapidly, and to avoid the loss of even a few moments' time in the operation of the elevator, it is customary for the person in charge of the cars to give a signal for the starting of the elevator before the loaded car reaches the position in which it is to be automatically stopped on the elevator. As a result of this practice, serious accidents have occurred by failure of the automatic stopping devices to properly perform their functions.

My object is to provide an absolutely reliable automatic car stop of this kind whereby the stop is automatically released to permit movement of the cars, and thereafter immediately restored to insure the stopping of the car passing onto the elevator.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Figure I is a vertical section showing a

portion of an elevator and two mine cars 55 movable across the floor of the elevator.

Fig. II is a view of the elevator, showing the automatic car stop as it appears immediately before the elevator reaches its lowermost position.

Fig. III is an enlarged section taken approximately on the line III-III, Fig. II.

A designates the vertically movable cage of a mine elevator provided with a floor or platform 1 on which rails 2 are secured. 65 When the elevator occupies its lowermost position, the rails 2 are alined with rails 2^a and 2^b. B and B' indicate mine cars movable across the elevator so as to pass from the rails 2^a to the rails 2^b. An elevator of 70 this type is ordinarily used to elevate loaded cars to the top of a mine shaft, where they are dumped and then lowered on the elevator. The car B' may be considered as an empty car to be removed from the elevator, 75 while the car B is a loaded car to be used in pushing the car B' from the elevator.

The bottom of each car is provided with a downwardly extending abutment 3 adapted to be confined by a car stop comprising a 80 trippable stop lever C and a yielding detent lever D, said levers being mounted between angle bars 4 on the floor of the elevator. The detent lever D is pivotally supported at 85 5 and provided with a spring 6 whereby its upper end is yieldingly held in the path of the abutment 3. 7 designates a releasing chain connected to the detent lever D and adapted to be operated by hand to displace said lever from the path of the abutment 3. 90

However, this detent lever D is ordinarily operated by the abutment 3 which can pass freely in one direction over the top of said lever. For example, when the car B is moved in the direction indicated by the arrow in Fig. I, its abutment 3 will pass over and depress the upper end of lever D, and immediately thereafter the spring 6 will restore said lever D to prevent retrograde movement of the car. When a car is pushed onto the elevator in this manner, the lever C serves as a stop to limit the movement of the car, and the car is thus stopped in a predetermined position on the elevator, where its abutment 3 is confined between the levers C 95 and D, as shown by Fig. II.

When the elevator reaches the position shown by Fig. I, the stop lever C is dis-

placed to the position shown by dotted lines, so as to release the car and permit it to move toward the rails 2^b. To illustrate this feature of the invention, I have shown 5 a long stop-displacing lever 8 pivoted to the elevator at 9 and provided with a weight 10 near its outer end. 11 designates a trippable arm pivoted to and depending from the stop lever C, said arm having an abutment 10 shoulder 12 adapted to extend into a notch at the top of an abutment 13 on the lever 8. 14 designates a weight located at the lower end of the trippable arm 11 and tending to retain the stop lever C in the position shown 15 by full lines in Figs. I and II. When the parts occupy the positions shown by Fig. II, the weight 14 tends to retain the arm 11 in engagement with the abutment 13. The lever 8 passes through a loop 15 (Figs. II 20 and III), and the lower end of this loop serves as means for limiting the downward movement of said lever 8 relative to the elevator. 16 designates a stationary stop, or abutment, located in the path of the lever 25 8 and adapted to be engaged by said lever for the purpose of transmitting movement to the stop lever C.

The means for releasing the trippable arm 11 from the abutment 13 comprises a tripping lever 17 pivoted at 18 to the elevator 30 and extending into the path of abutment 3 which is carried by the car. The lower end of tripping lever 17 may be provided with a roller adapted to engage the trippable 35 arm 11.

The operation of this device is as follows: Assuming that the elevator is moving downwardly from the position shown 40 by Fig. II, the free outer end of the stop-displacing lever 8 will engage the stationary abutment 16, and a continued downward movement of the elevator will then result in the transmission of movement from lever 8 to the arm 11, and the stop lever C 45 will thus be shifted from its operative position to the inoperative position shown by dotted lines in Fig. I.

When the stop lever C has been displaced in this manner, the car B' can be moved to 50 the right so as to pass from the elevator and onto the rails 2^b. During this movement of the car, its abutment 3 passes over the stop lever C and engages the upper end of tripping lever 17, thereby displacing arm 55 11 from the abutment 13 and permitting said arm to drop by gravity to the position shown by full lines in Fig. I. The downward movement of arm 11 will restore the stop lever C to its operative position. It 60 will now be understood that the stop lever C is automatically displaced to permit movement of the car, and at the very beginning of this movement the stop lever is quickly restored to serve as means for stopping an 65 other car.

In actual practice the car B passing onto the elevator is used to push the car B' from the elevator, as suggested by Fig. I. While these cars are in motion and when they are approximately in the positions illustrated by Fig. I, it is customary for the operator to give a signal for the starting of the elevator, and in view of this ordinary practice it is very desirable to provide a positive means for stopping the car in a predetermined position on the elevator. In the use of my device, the stop lever C is restored to its operative position some time before the cars reach the positions shown by Fig. I, and the abutment 3 on the car B will thereafter 70 75 80 pass over the detent lever D and positively engage the stop lever C.

After a car has been properly delivered to the elevator, the operating mechanism of my automatic device will be positioned as 85 shown by full lines in Fig. I, and when the elevator moves upwardly, the weighted lever 8 will rise from the stationary abutment so as to occupy the position shown by Fig. II, and the overhanging weight on the arm 11 90 95 will cause said arm to move to the position shown by Fig. II, wherein its shoulder 12 overlies the abutment 13 on the lever 8.

Under some unusual conditions, the stop lever C and its depending arm 11 may be 100 displaced to the positions shown by dotted lines in Fig. I, and the automatic mechanism may then fail to restore said parts to the positions shown by full lines. For example, after the parts C and 11 have been 105 displaced to the positions shown by dotted lines, a lump of coal may be accidentally positioned between the floor 1 and a part of lever C so as to retain said lever in the position shown by dotted lines. If the stop 110 lever should fail to return to the position shown by full lines when the tripping lever 17 is actuated, another part of my apparatus will become effective to either restore the stop lever or limit the motion of the car. 115 To accomplish this, the stop lever C is provided with an upwardly inclined resetting member 20 at one end, and when the other end of said lever is depressed to release the car, said member 20 is elevated to lie in the 120 path of the abutment 3 on the car, so if the arm 11 fails to drop by gravity when it is displaced by the tripping lever 17, the resetting member 20 will remain in an elevated position, where it will be engaged by the 125 abutment 3. In this event, the abutment 3 will strike the inclined top face of resetting member 20 and either restore the lever C or stop the car. If a lump of coal is located beneath the resetting member 20, the 130 abutment 3 will co-operate with said member 20 so as to crush the coal and at the same time restore the stop levers, but if some relatively firm object is preventing restoration of the stop lever, the abutment 3 will

coöperate with resetting member 20 to stop the car. This will occur immediately after the car begins its motion, so the operator will be quickly advised that the automatic 5 device is inoperative, and under these conditions the operator will not give the signal for the usual prompt starting of the elevator.

I claim:

10 1. The combination of an elevator, a car movable on said elevator, a car stop carried by the elevator, a stop-displacing member carried by said elevator, an abutment adapted to be engaged by said stop-displacing member to cause operation thereof, trippable means whereby motion is transmitted from said stop-displacing member to said car stop so as to displace the stop from its operative position, and a car-actuated tripping member 15 whereby said trippable means is displaced to restore said car stop, said abutment being engaged by said stop-displacing member when the elevator is positioned to receive the car, and said car-actuated tripping member 20 being carried by the elevator so as to coöperate with said trippable means while the car is moving on the elevator.

2. The combination of an elevator having tracks, a car movable on said tracks and provided with an extended abutment, a car stop carried by said elevator and comprising a yielding detent lever and a trippable stop lever between which said extended abutment may be confined, a stop-displacing lever carried by said elevator, a stationary abutment in the path of said stop-displacing lever, a trippable arm pivoted to and depending from said trippable stop lever, said trippable arm having a shoulder adapted to be engaged 35 by said stop-displacing lever, so as to displace said trippable stop lever from its operative position, and a car-actuated tripping lever whereby said trippable arm is released from said stop-displacing lever to restore 40 said trippable stop lever, said car-actuated tripping lever being pivoted to the elevator and extended into the path of a part of the car.

3. The combination of an elevator, a car 50 movable on said elevator, a car stop carried by the elevator, a stop-displacing member carried by said elevator, an abutment adapted to be engaged by said stop-displacing member to cause operation thereof, trippable means whereby motion is transmitted from

said stop-displacing member to said car stop so as to displace the stop from its operative position, and a car-actuated tripping member whereby said trippable means is displaced to restore said car stop, said car stop 60 being provided with a resetting extension located in the path of the car when said car stop occupies its inoperative position.

4. The combination of an elevator, a car movable on said elevator, a car stop carried 65 by the elevator, a stop-displacing member carried by said elevator, an abutment adapted to be engaged by said stop-displacing member to cause operation thereof, trippable means whereby motion is transmitted from 70 said stop-displacing member to said car stop so as to displace the stop from its operative position, and a car-actuated tripping member whereby said trippable means is displaced to restore said car stop, said car stop being 75 provided with a resetting extension located in the path of the car when said car stop occupies its inoperative position, and said car-actuated tripping member being located in advance of said resetting extension so as 80 to normally restore said car stop before the car occupies an operative position relative to said extension.

5. The combination of an elevator, a car 85 movable on said elevator, a car stop carried by the elevator, a stop-displacing member carried by said elevator, an abutment adapted to be engaged by said stop-displacing member to cause operation thereof, trippable means whereby motion is transmitted from 90 said stop-displacing member to said car-stop so as to displace the stop from its operative position, and a car-actuated tripping member whereby said trippable means is displaced to restore said car stop, said car stop being 95 in the form of a lever having an upwardly extending stop member at one end and an upwardly extending resetting member at the opposite end, said resetting member being in the path of the car when said stop member occupies its inoperative position, and said car-actuated tripping member being located in advance of said resetting member 100 so as to normally restore said car stop before the car occupies an operative position relative to said resetting member.

In testimony that I claim the foregoing I hereunto affix my signature.

WALTER S. ALLYN.
